FLASK

Hayden W. Coulthurst, Cranston, R.I., assignor to Textron Inc., Providence, R.I., a corporation of Rhode Island

Filed Aug. 3, 1965, Ser. No. 86,417

Term of patent 14 years

(Cl. D58—8)

FIG. 1

FIG. 2

FIG. 3

FIG. 4

FIG. 5

FIG. 1 is a perspective view of a flask, showing my new design;

FIG. 2 is a front elevational view;

FIG. 3 is a rear elevational view;

FIG. 4 is an end elevational view looking from the right of FIG. 1; and

FIG. 5 is a top plan view thereof.

The stippling represents a screw cap having a metallic appearance and a matching permanently attached over-cap having a metallic appearance.

The characteristic feature of my design resides in the combination on the flask disclosed of the integral over-cap having a metallic appearance and substantially flat, downwardly sloping shoulders which are rounded at their edges at the junction with the conforming skirt, said over-cap covering substantially the upper third of the transparent container body and terminating shortly above the side ribs thereof, all as shown.

I claim:

The ornamental design for a flask, substantially as shown and described.
